UNITED STATES PATENT OFFICE.

DELBERT J. RAY, OF ARKANSAS CITY, KANSAS.

MULTIPLIER APPLIANCE FOR CAMERAS.

Application filed March 7, 1928. Serial No. 259,794.

The present invention relates to a multiplier device for cameras, and has for its prime object to provide a device of this nature, which reduces the time and energy expended 5 in making several pictures on one film pack and a multiplier appliance is designed especially for photographers making small photographs, such as ping pong.

Another very important object of the invention resides in the provision of an appliance of this nature having a film pack carrier, which may be adjusted horizontally and vertically, so that a plurality of exposures may be had on a single film.

15 A still further very important object of the invention resides in the provision of an appliance of this nature, which is simple in its construction, inexpensive to manufacture, thoroughly efficient and reliable in operation, 20 and otherwise well adapted for the purpose for which it is designed.

With the above and numerous other objects in view, as will appear as the description proceeds, the invention resides in certain novel 25 features of construction, and in the combination and arrangement of parts as may be hereinafter more fully described and claimed.

In the drawings:

Figure 1 is a rear elevation of the appliance 30 showing the film pack carrier in one position.

Figure 2 is another view showing the film pack carrier in another position.

Figure 3 is a vertical section therethrough, taken substantially on the line 3—3 of Figure 35 2.

Figure 4 is a horizontal section, taken substantially on the line 4—4 of Figure 2.

Figure 5 is a plan view of a film indicating the spaces where a plurality of exposures 40 have taken place.

Referring to the drawings in detail, it will be seen that the numeral 5 denotes a plate, which is attached to the back of a camera 6, so that the opening 7 in the central portion 45 of the plate registers with the interior of the camera. This plate 5 is preferably rectangular in formation, having its longitudinal dimension disposed vertically. A stop cleat 8 is secured to the upper end of the plate 5 and 50 has a pin 9 projecting therefrom. A plate 10 is slidably mounted on the plate 5 and for this purpose is provided with a pair of grooved cleats 11 which receive the longitudinal edges of the plate 5. The plate is reduced beyond

the cleats 11 to extend to each side of the 55 plate 5. The plate 10 is formed centrally with a vertically disposed slot 12, in which is slidable a plate 13 fixed to the plate 5 and having an opening 14, registering with the opening 7. A pair of longitudinal horizontal 60 channels 15 are fixed in spaced parallelism on the plate 10, one adjacent each longitudinal edge of the ends of said plate 10 and the channels are provided in opposed faces of the cleats. A rectangular holder 65 frame 16 is slidable in the channels of the cleats 15 and is provided at its inner face with inwardly directed flanges 17. A cover 18 slips under a member 19 projecting from a bar 20 on one end of the frame 16 and the other end 70 is provided with a pair of extensions 21, with one of which is engageable a pivoted cap 22, for holding the cover in place. A film pack 23 is disposed in the holder frame, between the flange 17 and the cover 18, so that the tabs 24 75 project out one end between the extensions 21. This film pack is conventional and well known in the art. The frame 18 has an extension 25 at one end with a transparent panel 26 therein. A sheet 27 is interposed between the plate 5 and the plate 13 and extends a slight distance between the plates 5 and 10, for the purpose of keeping out light. The numeral 28 denotes a film in the film pack 23 on which eight exposures may be made, as indicated by the dotted line, defining spaces 80 indicated by the letters A, B, C, D, E, F, G, and H.

With the parts disposed as shown in Figure 1, it will be seen that the photographer may 90 obtain the proper focus of the camera by looking through the panel 26 which registers with openings 14 and 17. After the focus has been made, the pack frame may be slid to the left until space E registers with the opening 95 14, at which time, a catch 29 will engage one of the notches 30 in the edge of plate 31 on the upper cleat 15, and the first exposure may be made. Then the frame may be moved over to the right for the second focus, and then the 100 frame may be moved to the left to bring space F opposite the openings 14 and 17 and another exposure made, the parts 29 at this time being engaged with the second notch 30. Pictures G and H are made in like manner as 105 will be apparent. When exposure H is made, the frame extension 25 abuts a stop 32, on the end of the plate 10. A spring catch 33 has

an opening receiving the pin 9, for holding the plate in abutment with the cleat 8, during these exposures.

By releasing the catch 33 from the pin, the plate 10 will slide down, until the upper wall of the slot 12 abuts the top edge of the plate 13 and then exposures A, B, C, and D may be made, in a similar manner to exposures E, F, G, and H, as will be quite apparent. A removal stop 35 is provided, at the other end of the upper cleat 15, to prevent the top frame from coming all of the way out of the cleat.

In the practical embodiment of the invention now in use, I make eight pictures to a film, size $2\frac{1}{2}$ by $4\frac{1}{4}$ thus obtaining ninety-six pictures to a twelve exposure film pack. This appliance may be made of wood or metal or both. The size of the film pack used may vary according to the size of picture desired, and of course, the appliance may be built in any size desired.

It is thought that the construction, operation and advantages of the invention will now be quite apparent to those skilled in this art without a more detailed description thereof. The present embodiment of the invention has been disclosed in detail, merely by way of example, since in actual practice it attains the features of advantage enumerated as desirable in the statement of the invention and the above description.

It is apparent that changes in the details of construction, and in the combination and arrangement of parts may be resorted to, without departing from the spirit or scope of the invention as hereinafter claimed, or sacrificing any of its advantages.

Having thus described my invention, what I claim as new is:

In a device of the class described, including a fixed rectangular plate having an opening adapted for attachment to the rear of the camera, said plate having its length vertically disposed and the opening in communication with the interior of the camera, a second rectangular plate formed with a central vertically disposed slot, a projection on said first mentioned plate adjacent the opening thereof to engage in said slot on the second plate, a pair of grooved cleats disposed intermediate the ends of said second mentioned plate overlapping the side edges of said first mentioned plate to permit vertical movement with respect to the latter, a pair of horizontal channeled cleats extending longitudinally on the outer face adjacent each longitudinal edge of said second plate, a rectangular film pack holder frame slidably mounted within said pair of longitudinally extending cleats, said film pack frame provided with a flange projecting interiorly thereof at its inner face and a detachable cover flush with its outer face for the purpose of supporting a package of films on the interior of said frame between said flange and cover, cooperable means on the first and second plates for detachably holding said second plate in different adjusted positions with respect to the first plate, and cooperable means on the second plate and said film pack holder frame for selectively locking the latter in adjusted position with respect to the second plate.

In testimony whereof I affix my signature.

DELBERT J. RAY.
